US00D484650S

(12) United States Design Patent (10) Patent No.: US D484,650 S
Meath (45) Date of Patent: * Dec. 30, 2003

(54) RETRACTABLE DOG LEASH

(76) Inventor: Franklin Meath, 1528 Payne Ave., St. Paul, MN (US) 55101

() Term: 14 Years

(21) Appl. No.: 29/175,833

(22) Filed: Feb. 11, 2003

(51) LOC (7) Cl. 30-04

(52) U.S. Cl. D30/153; 119/794

(58) Field of Search D30/153, 154, D30/160; 119/796, 769, 794-795

(56) References Cited

U.S. PATENT DOCUMENTS

D216,897 S * 3/1970 Meath D30/153
D269,301 S * 6/1983 Deibert D30/153
D298,579 S * 11/1988 Brummett D30/153
4,889,551 A * 12/1989 Oda et al. 504/271
5,456,214 A * 10/1995 Quilling 119/795

5,595,143 A * 1/1997 Alberti 119/794

* cited by examiner

Primary Examiner—Pamela Burgess

(74) Attorney, Agent, or Firm—D L Tschida

(57) CLAIM

The ornamental design for a retractable dog leash, as shown and described.

DESCRIPTION

FIG. 1 is a perspective drawing showing top, rear and left side views of my new design for a retractable dog leash.

FIG. 2 is a perspective drawing showing top, front and left side views of my new design for a retractable dog leash.

FIG. 3 is a perspective drawing showing bottom, rear and right side views of my new design for a retractable dog leash; and,

FIG. 4 is a perspective drawing showing bottom, front and right side views of my new design for a retractable dog leash, with the bone-shaped handgrip removed for clarity of disclosure.

1 Claim, 1 Drawing Sheet

FIG. 1

FIG. 2

FIG. 3

FIG. 4